UNITED STATES PATENT OFFICE

111,508

DESIGN FOR A PHONOGRAPH CABINET

William Corcoran, San Francisco, Calif.

Application June 21, 1938, Serial No. 77,973

Term of patent 3½ years

To all whom it may concern:

Be it known that I, William Corcoran, a citizen of the United States, residing in the city and county of San Francisco, State of California, have invented a new, original, and ornamental Design for a Phonograph Cabinet, of which the following is a specification, reference being had to the accompanying drawing, forming part thereof, showing the top, front, and left-hand side, the right-hand side being identical to the left-hand side.

I claim:

The ornamental design for a phonograph cabinet, as shown and described.

WILLIAM CORCORAN.
